United States Patent Office

Des. 186,316
Patented Oct. 13, 1959

186,316

KEYBOARD UNIT

Robert N. Flanders, Monrovia, Calif., assignor to
F. L. Moseley Co., a corporation of California

Application May 17, 1957, Serial No. 46,211

Term of patent 14 years

(Cl. D26—5)

Fig. 1.

Fig. 2.

Fig. 3.

Fig. 1 is a perspective view of a keyboard unit, showing my new design;

Fig. 2 is a side elevational view of the keyboard unit of Fig. 1 showing the side opposite to that disclosed in Fig. 1; and

Fig. 3 is a rear elevational view thereof.

I claim:

The ornamental design for a keyboard unit, as shown and described.
